UNITED STATES PATENT OFFICE

HUGH MALCOLM McCORMICK, OF HUNTINGTON, INDIANA

PIPE FOR SMOKING TOBACCO

Application filed January 21, 1929. Serial No. 333,947.

My invention consists of means for more evenly and completely burning the charge of tobacco in the bowl of a pipe, thereby lessening the residue of nicotine and other chemicals in the bottom of said bowl, lessening the quantity of nicotine and other chemicals entering and adhering to the walls of the orifice or orifices of the pipe-stem, and fully consuming the dottle of the charge of 10 tobacco in the bottom of the bowl; producing, as a consequence, a relatively dry, sweet and fragrant smoke without necessarily altering either the shape, size, weight or use of either pipe-bowl or pipe stem, and all 15 without the addition of any extraneous part or parts; or, specially shaped bowls, or stem-bases next bowls, or both stem-bases and bowls, can be made at will in a wide variety of designs, to emphasize and elaborate my 20 invention.

The bane of tobacco smoking is the more or less rapid accumulation of moisture in and from charges of tobacco in the lower portion of the pipe bowl. From such moist 25 portion or such charges, the smoker draws a steady flow of poisonous nicotine and other chemicals and gases in combination, the total tending to produce a damp and acrid smoke.

In addition, particles of moisture-soaked 30 tobacco, commonly termed slugs, together with considerable quantities of liquid, are frequently drawn into the mouth by the smoker's suction through the orifice or canal of the pipe stem, often disagreeably spoiling 35 the sedative pleasure to be derived from smoking properly and sufficiently consumed tobacco.

The reasons for incomplete and imperfect 40 combustion or oxidation of charges of tobacco in the bowl of a pipe are:

1. Lack of sufficient aeration in the surface burning zone, and in the charge below the burning zone;
2. Lack of properly distributed and balanced means for inducing adequate and constant circulation of air upon and through the charge of tobacco in the bowl of the pipe, in response to the draft or suction exerted by the smoker through the orifice or conduit 50 of the pipe stem.

After lighting the charge of tobacco in the bowl of a pipe it must be consumed by forcing a draft of air from top to bottom of said charge, and the completeness of combustion depends upon the presence, in said 55 charge, of sufficient oxygen at all times to insure full and even oxidation. The defect of pipes for smoking tobacco is that they fail to provide means to induce enough and sufficiently diffused circulation of air through 60 charges of tobacco in their bowls. Prevailing provision of only one orifice, channel or canal, connecting the base of the bowl of the pipe, through the stem thereof, with the mouth of the smoker, does not permit of adequate 65 atmospheric inhalation and circulation through said charge, to either fully or properly consume it.

I overcome such defect as follows:

Figure 1 shows an oblique side view of a 70 tobacco-pipe equipped with a plurality (*m*, *n*, *o*,) of orifices or canals converging in the stem, a short distance outside the bowl, into one conduit traversing the remainder of the 75 stem.

Figure 2 shows a cross section of the bowl of a pipe, said bowl being equipped with a plurality (*a*, *b*, *c*,) of apertures.

Fig. 3 is a side elevation partly in section of an alternate form of pipe in which a single auxiliary passage is provided instead of two auxiliary passages, as shown in Figs. 1 and 2.

Fig. 4 is a transverse sectional elevation on the line 4—4 of Fig. 3.

Instead of employing only one aperture outlet from the bowl of the pipe into the stem of the pipe, I employ a plurality of orifices or canals, and these may converge into one central conduit or canal within the wall of the bowl, or within the stem at any proper distance outside the bowl of the pipe which the pipe manufacturer or pipe smoker desires.

The mechanical operation of tobacco-pipe 95 smoking being a down-draft (air being drawn against the fired top of the charge of tobacco in the bowl of the pipe, through such fired zone and below it through the unlighted portion of the charge beneath, then into the 100

aperture leading from or near the base of the bowl into the stem and along this little conduit to issue, at its opposite end, into the mouth of the user, such air carrying with it, as products of combustion, aromatic juices and gases, the whole commonly termed tobacco smoke) it follows that the more even, diffuse, gradual and complete the combustion of the tobacco charge, the greater the enjoyment of the smoker, and the less harmful the habitual use of tobacco.

In using my invention, I have noted the following practical improvements and advantages:

- 15 1. A charge of tobacco in the bowl of a pipe will burn steadily and evenly into dry ash, from top to bottom of bowl;
- 20 2. The conduits from the bowl into the main canal of the pipe stem, and the main canal itself, tend to keep free of accumulations longer, and are much drier than a single canal;
- 25 3. The smoke drawn through the pipe stem canal is pleasantly dry, fragrant and warm. Adequate combustion of the tobacco charge does not destroy the desirable flavors and aromas thereof. Slugs and particles of liquid seem wholly absent.

A distinct advantage of my invention is 30 that it costs extremely little extra to install; two, three or more apertures in the bowl or in both bowl and stem can be provided almost as easily and cheaply as one, and no extra or additional part is required.

35 I respectfully submit that the extreme simplicity of my invention (its instant obviousness upon trial) should be no bar to obtaining Letters Patent therefor. I have myself used a variety of devices invented and made by others, devised and intended to 40 keep tobacco-pipe stem conduits free of obstructive accumulations, at intervals for thirty years. None of said devices keep pipe-bowl bottoms clean and dry, or otherwise effect my results, and I pondered over and 45 frequently discussed the problems now solved by my invention, with others at intervals for many years, before I finally reasoned out what should be done to properly 50 consume a charge of tobacco in a pipe-bowl, and thereafter discovered, and proved by experiments, that my reasoning was correct.

I therefore claim broadly the discovery 55 that tobacco-pipe-bowls and stem-conduits have been heretofore insufficiently aerated; that adequate aeration is required to effectively, wholly and cleanly consume charges of tobacco in the bowls of tobacco pipes, and to keep the conduits of the stems thereof 60 relatively free of accumulations of oily juices and saturated particles, during the mechanical operation commonly termed "pipe smoking"; though my illustration of means for accomplishing such effective aeration is of 65 necessity limited in a specification. A great

number and variety of applications of my discovery and invention by others are possible, therefore it is manifestly both unnecessary and impossible for me to disclose more than my basic discovery and an effective means for utilizing it. Tobacco pipes have been smoked by white men for hundreds of years, and by North American Indians for an unknown period before that. I believe that my discovery, and my means for making it usefully effective, as set forth in this specification, constitute one of the most pleasing, valuable and practically important contributions to the welfare of those addicted to the genial habit of tobacco-pipe-smoking, in the whole history of the usage of tobacco-pipes.

Every pipe smoker wishes to smell, taste and enjoy the fragrance and flavor of his tobacco. My invention tends to improve the quality of such fragrance and flavor by reducing excess moisture generated in the pipe-bowl and thereafter transmitted through the conduit of the pipe-stem, in the act of smoking, also eliminates disagreeable and objectionable particles of matter carried by such excess moisture, and, finally, consumes the unhealthy and wasteful saturated dottle at the base of the bowl of the pipe and leaves a dry clean bowl-bottom in place of a wet bottom occupied by a bitter and soggy residue.

My invention is equally useful and applicable to curved as well as straight tobacco-pipe-stems. I prefer curved stems myself, and use only two apertures as shown on Figs. 3 and 4 at *e* and *f* from pipe-bowl to pipe-stem-conduit, the upper aperture *e* directly above the lower *f*, the two converging into one pipe-stem-conduit about one-half-inch outside the pipe-bowl. In commercial manufacture, however, I believe three apertures will be generally preferred, as offering better balanced aeration.

Having thus shown and described my discovery and invention, I claim:

A pipe comprising a bowl having a stem section connected thereto, a bit section having a bit thereon connected to said stem section, said stem section having a plurality of superposed smoking ducts converging from the bowl and directly joining a common duct terminating in the outer end of said bit section, the smoke passage from the bowl to the end of said bit section being continuous and uninterrupted by cavities or wells.
